(57) CLAIM

The ornamental design for flatware, as shown and described.

DESCRIPTION

FIG. 1 is a perspective view of flatware showing our new design.

FIG. 2 is a front plan view thereof, the back plan view being a mirror image thereof;

FIG. 3 is a right side view thereof, the left side view being a mirror image thereof;

FIG. 4 is a top view thereof; and,

FIG. 5 is a bottom view thereof opposite to that view shown in FIG. 4.

The broken line showing the fork tines is for illustrative purposes only and forms no part of the claimed design.
